UNITED STATES PATENT OFFICE.

MICHAEL REDLINGER AND CHARLES MORGAN, OF FREEPORT, ILLINOIS,
ASSIGNORS TO THE ARCADE MANUFACTURING COMPANY, OF SAME
PLACE.

STOVEPIPE-DAMPER.

SPECIFICATION forming part of Letters Patent No. 520,379, dated May 22, 1894.

Application filed January 26, 1894. Serial No. 498,077. (No model.)

To all whom it may concern:

Be it known that we, MICHAEL REDLINGER and CHARLES MORGAN, citizens of the United States of America, residing at Freeport, in the county of Stephenson and State of Illinois, have invented certain new and useful Improvements in Stovepipe-Dampers, of which the following is a specification.

Our invention relates to improvements in stovepipe dampers, and more particularly to improvements in the shanks of such dampers and the attachment of handles thereto.

The invention is fully described and explained in this specification and shown in the accompanying drawings, in which—

Figure 1 is a plan of a damper embodying our improvements. Fig. 2 is a plan of a portion of the shank, the handle being shown in section. Fig. 3 is a longitudinal section of a portion of the shank; and Fig. 4 is a transverse section of the shank and a part of the damper blade through the line $x-x$, Fig. 1.

In the views, A is a preferably circular damper blade, formed with the usual diametrical slot which is crossed by bridges or clasps, a, a' , lying on opposite faces of the blade and connecting its two halves. A detachable shank, B, is adapted to lie between the clasps, a, a' , and terminates at one end in a yoke, C, adapted to receive and partly encircle a transverse handle, D. A thimble, T, encircles the shank, and a spring, S, also encircling the shank and lying between the yoke and the thimble, tends to press the latter toward the edge of the blade. The shank is provided with two lugs, b, b' , adapted to lie against the opposite faces of the blade when the shank is in working relation thereto and the inner margin of one of the halves of the blade is formed with a notch, N, adapted to permit the passage of the lug, b' , when the shank is partially rotated to bring it into working position. The shank is of less diameter than the inner curve of the clasps, a, a' , and is provided at a suitable point with a lug, b^2 , projecting sufficiently to bind against the inner face of the corresponding bridge, a , and hold the shank rigidly in position. The lug, b^2 , is of slight width and it may therefore be easily ground or otherwise fitted to the bridge

which it engages, and for this reason it is greatly preferable to make the bridge of greater internal diameter than the diameter of the shank instead of fitting the entire shank to the inner surface of the bridge. The shank 55 terminates at one end in the yoke, C, adapted to clasp a wooden handle, D, of any desired form, and a tang, C', is formed integral with the yoke and is so placed as to enter a hole in the center of the handle. The outer face 60 of the tang is provided with teeth, c, adapted to enter the wood of the handle and the inner face is beveled longitudinally as clearly indicated in Figs. 2 and 3, so as to form a wedge having its base at its intersection with 65 the yoke. A wedge, C², having one face beveled to correspond with the beveled face of the tang C', is provided on its outer cylindrical face with teeth, c, like those upon the tang, and its largest end or base has a head, 70 C³, preferably of about the same diameter as that of the combined tang and wedge.

To apply the handle to the shank the opening in the handle is slipped over the tang until the handle is seated in the yoke. The 75 wedge is then inserted and driven inward to the position shown in Fig. 2 and the parts are all so proportioned that when the wedge is in this position, the teeth upon the wedge and tang are forced into the wood of the handle 80 and thus prevent longitudinal movement of the tang and wedge with reference to each other. The handle is thus held securely in place and is permanently fastened upon the shank. The fastening thus constructed is extremely cheap and simple and we have found in actual practice that it is perfectly effective.

Having now described and explained our invention, what we claim as new, and desire to secure by Letters Patent, is—

1. In a damper, the combination with a handle formed with a suitable opening, of a shank terminating in a tang having one of its faces beveled and its opposite face serrated, and a wedge having similar beveled and serrated faces, said tang and wedge being adapted to enter the opening in the handle from opposite directions, and when wholly within the opening to embed their serrations in the handle.

2. The combination with the shank, B, having the yoke, C, and tang, C', of the wedge, C', and handle, D, the tang and wedge having their contiguous faces beveled and their external faces serrated, the handle, D, being formed with an opening adapted to receive the tang and wedge and the yoke, C, being adapted to clasp the handle when in opera-

tive position; substantially as shown and described.

MICHAEL REDLINGER.
CHARLES MORGAN.
